UNITED STATES PATENT OFFICE.

THADDEUS A. NOLAN, OF CINCINNATI, OHIO.

FIREPROOF MAGAZINE FOR PICTURE-FILMS.

No. 921,273.

Specification of Letters Patent.

Patented May 11, 1909.

Application filed September 14, 1907. Serial No. 892,909.

To all whom it may concern:

Be it known that I, THADDEUS A. NOLAN, a citizen of the United States, residing in Cincinnati, county of Hamilton, and State of Ohio, have invented certain new and useful Improvements in Fireproof Magazines for Picture-films, of which the following is a full, clear, and exact description, reference being had to the accompanying drawings, forming part of the specification.

The film for moving picture machines is usually mounted on a reel suitably journaled, so as to feed the picture film at a rapid and constant rate of speed to the machine. This film is ordinarily dry and brittle, and exceedingly fragile. The film also is highly inflammable, and under the concentrated rays from the lantern, it very readily takes fire, and constant precautions have to be taken to prevent ignition of the film.

It is the purpose of my invention to provide a magazine for the film, which shall prevent the destruction of the film, which is mounted on the reel, should the exposed portion take fire, and in which magazine the film shall be maintained in moist condition, so as to strengthen and render it more pliable, and less likely to become damaged, or destroyed, in passing through the machine, at the same time that the film itself is rendered less inflammable.

In the drawings Figure 1 is a perspective view of my improved fire proof magazine open. Fig. 2 is a similar view of the magazine closed, and Fig. 3 is a central horizontal section of the magazine.

1 is a metal box or case, provided with the hinged flanged lid 2 to close down over the sides of the case.

3 is the reel, upon which the picture film is mounted, journaled on the spindle 4, which has its bearing in the bottom of the case on one side, and in the clip 5 secured to the lid 2, arranged to engage the opposite end of the spindle when the lid is closed.

The interior of the case outside the periphery of the reel is provided with a wire gauze partition 6, which completely encircles the reel, or when the reel is of a size to com-

pletely fill the case, the corners of the rectangular compartment are provided with the wire gauze partitions. The spaces beyond the partitions are provided with hinged lids 7—7, which are preferably flanged to come down over the edge of the wire gauze, and 8—8 are catches for holding the lids shut. Within the space formed by these partitions at the corners of the box, I place sponges or other absorbent material 15, properly dampened with water to lade the atmosphere 60 within the case when the lid is closed with moisture.

For the delivery of the film from the case, I provide a slotted opening in one of the side walls at 9, and in this opening are mounted metal rollers 10—10, between which the film is passed. These rollers 10 completely fill up the opening in the case, and the space between the rollers, while wide enough to permit of the ready delivery of the film between the rollers, is so narrow, and the heat is so rapidly conducted away, that the flame from the film, which may have been accidentally ignited outside the case, cannot advance within the case.

11 is a holder to which the case is secured at the back, and by which the magazine is secured to the frame of the moving picture machine.

12 is a clasp for locking the lid shut.

Having thus described my invention, what I claim as new and desire to secure by Letters Patent is:

A magazine for moving picture films, comprising a metal case with a hinged lid therefor, a reel for the picture films journaled therein, an opening for the passage of the film, with metal rollers mounted to close said opening, and between which rollers the films pass, and a separate compartment with a wire gauze partition surrounding said reel within said case with dampened absorbent material therein to render the atmosphere moist within the case, when the lid is closed.

THADDEUS A. NOLAN.
